CONTROLLING MECHANISM FOR CASH
REGISTERS AND CALCULATING MA-
CHINES

Ernst Breitling, Essen, Germany, assignor, by
mesne assignments, to The National Cash
Register Co., Dayton, Ohio, a corporation of
Maryland

Application June 28, 1930, Serial No. 464,614
In Germany July 11, 1929

14 Claims. (Cl. 235—7)

This invention relates to cash registers and calculating machines having totalizers in which items may be entered and the totals may be taken therefrom. As is well known in the art, the operation of certain mechanisms of the machine must be different for adding items, than for taking a total. In machines of the class to which the present invention is shown attached, the control of these mechanisms is accomplished by the adjustment of a total lever.

In order to take as much load as possible off of the total lever, the present invention provides a novel means for controlling said mechanisms by the depression of an amount key; that is to say, the operation of the total lever does not affect the control of these mechanisms, said control being dependent upon the depression, or non-depression, of an amount key.

The present invention is applied to a machine adapted to record single item transactions; multiple item transactions, including the entry of a plurality of items and printing a total thereof.

Certain mechanisms, including the operation of customer counters, the indicator flash plate, and the opening of the cash drawer, are set in operation when entering a single item transaction; or when printing multiple item totals, but not when entering an item of a multiple item transaction. To prevent the operation of these parts when an amount key is depressed for entering an item of a multiple transaction, a special key *Sa* is provided, which, when depressed, uncouples the mechanism coupled by the depression of an amount key.

The distinction between the registration of an independent single item and a multiple item total during the course of the business day is best illustrated by comparing two kinds of customers. One type of customer comes into the establishment needing only a single item. The payment for this single item is registered upon the machine, at which time several associated mechanisms in the machine are actuated. Thus the money drawer must be released to deposit the payment and make the necessary change; the flash plate of the indicating mechanism is operated for the benefit of the customer, and one of several item counters is advanced one unit to obtain a count, for instance, of the number of people served. The other type of customer comes into the establishment needing several items; for instance, five. Rather than actuate each one of the above mechanisms at the registration of each one of the items, which serves no useful purpose and which imposes a great deal

of unnecessary wear upon the machine parts, the machine operates in such a manner that the several items are entered, as on an adding machine, and not until the total is obtained are the several associated mechanisms actuated to allow the termination of the transaction with that particular customer in the same manner as in dealing with a customer who made the purchase of only a single item.

In order that my invention can be more readily understood, an embodiment of the same is illustrated by way of example in the accompanying drawings in which

Figure 1 is a lateral view of the various members belonging to one order of the machine, with the key board, differential mechanism, total taking mechanism, and totalizer.

Figure 2 is a lateral view of the controlling mechanism for the total taking mechanism in position of rest.

Figure 3 is a detail thereof with the parts concerned in operative position.

Figure 4 is a lateral view of the controlling mechanism that causes formation of totals from several items or multiple-item totals.

Figure 5 is a lateral view of the means for driving the item counting mechanism.

Figure 6 is a lateral view of the members controlling the flash-plate of the indicating mechanism.

Figure 7 is a lateral view of the money drawer controlling mechanism.

Figure 8 is a diagrammatic top view of the setting means of the machine, and

Figure 9 is a lateral view of the differential mechanism adjacent the bank of sellers' keys.

The setting mechanism of the cash register illustrated in these drawings comprises five rows of amount keys 11, Figure 8, a total lever 12 which can be set to three positions, viz: *Ad* (addition), *ES* (grand total), and *ZS* (sub-total), and two rows of special keys 13, 14. Row 13 comprises six motor keys 1 to 6 designed as sellers' keys, and a motor key *Sx* to be depressed to take the multiple item totals of several items. The row 14 comprises a motor key 14a (*) serving to take a total from the main totalizer, an accumulating key 14b (*Sa*) for the selection of a totalizer for the multiple item transactions, that means causing entrainment during introduction of the amount, of a special totalizer (multiple-item totalizer), and a key 14c denoted "clear", causing an idle or money changing operation. The "clear" key can be depressed only in connection with one of the six sellers' keys.

55

It is to be seen from the foregoing that three kinds of totalizers are present in the machine, viz: a main totalizer, sellers' totalizers and the multiple-item totalizer mentioned. These totalizers are mounted on the shafts 15, 16, 17, Figure 1. Shaft 15 carries the main totalizer which is engaged upon entry of all items and therefore, on termination of the business hours, indicates the running total from all items entered, shaft 16 carries six sellers' totalizers in which the items are entered additively and subdivided according to six sellers, while shaft 17 carries the multiple-item totalizer which, as mentioned, serves for the formation of totals of several items by being engaged by depression of accumulating key Sa, Figure 8, upon a certain number of items being entered subsequently. The individual totalizers are selected and engaged for operation in a manner known in the prior art by shifting the shafts 15, 16, 17 through the intermediary of riders 18 and of internal teeth 19 of the counting wheels 21. The mechanism for selecting one of the totalizer lines 15, 16, or 17, and the selection of a totalizer on a line, are not shown herein, but these are shown and described in the French Patent No. 665,190 and in a corresponding United States application Serial No. 296,445. In the present machine, depression of a seller's key selects a seller's totalizer on line 16 for engagement during an adding operation of the machine. Depression of the Sa key selects the multiple item totalizer on shaft 17 for engagement during an adding operation of the machine. The main totalizer is selected during all adding operations.

During total taking operations, the engagement of the multiple item totalizer on shaft 17 is determined by the depressed key Sa, which remains depressed at the end of the item entry operation, together with the depression of the Sx key. The non-depression of an amount key, when the Sa and Sx keys are depressed, causes the machine to go through a total taking operation. Therefore, when taking a total from the multiple item totalizer, both keys Sa and Sx must be in depressed position. This prevents the totalizers on lines 16 and 17 from being engaged. When it is desired to take a total from the main totalizer on shaft 15, only the key * is depressed, and when a total is taken from a seller's totalizer, only a seller's key 13 is depressed. The riders 18 are in permanent connection (not shown in detail) with differential wheels 22 which through intermediate wheels 23, 24 are in mesh with teeth 25 of main differential actuators 27 mounted on fixed journals 26. The main differential actuators 27, by means of a stop 28, co-operate with the foot of the depressed amount key 11 and are rocked up to the latter with a scissors movement by means of a differential gear. This gear comprises a transverse lever 29 which through a link 31 pivoted thereon by a pin 30 is hinged to a lever 32 fixed to a driving shaft 33, Figure 1. Pin 30 is carried by the free end of a lever 50 adapted to swing on a fixed journal 40. The transverse lever 29 further permanently engages the main differential actuator 27 by means of a block 34 and by means of another block 35 on auxiliary differential actuator 36. The latter possesses a stop 37 which co-operates with the foot of the depressed key. As soon as, after depression of a key 11, shaft 33 has been turned to such an extent that pin 30 is in coaxial alinement with pin 26, then the two stops 28 and 37 have been moved from both sides up to the foot of the depressed key, the main differential actuator 27

having executed a motion of an amplitude corresponding to the key depressed. This motion is transmitted to the engaged totalizers by means of the intermediate wheels 24, 23, 22. A differential setting member 201 is furthermore mounted upon shaft 26, the pin 209 of which is embraced by differential members 27, 36 and in addition operations is set in accordance with the amount key which is depressed and in total-taking operations, in accordance with the amount contained in the adding wheels. The differential member 201 has a toothed portion 202 which meshes with gear wheel 210 to set the appurtenant type wheel, and with gear wheel 211, loosely mounted on shaft 206, to set the appurtenant indicating mechanism through gear wheel 212.

The described differential actuating mechanism is used for taking totals in the following manner.

On the auxiliary differential actuator 36 is provided a locking surface 38 in the path of which, previous to the commencement of a total taking operation, is placed a roller 39 mounted on a two-armed lever 42, 43 fixedly mounted upon a hollow shaft 41, which in turn is rotatably mounted upon shaft 206. During normal registering operations, roller 39 is not in the path of surface 38. A mode-of-operation lever 12 (Fig. 8) controls the position of roller 39 by a suitable transmitting mechanism such as that disclosed in Patent No. 1,899,455. Arm 43 has a nose-shaped end and co-operates with a series of locking teeth 44 riveted to the main differential actuator 27. Now, when in the position of the parts illustrated in Figure 1, the transverse lever 29 has imparted to it the normal driving motion by shaft 33, this motion is transmitted to the main differential actuator 27 only, since the auxiliary actuator 36 first remains at rest due to its being locked by roller 39 that engages face 38. This motion of the main differential actuator 27 causes a backward rotation, or in the direction shown by the arrow in Fig. 3, of the counting wheel 21 coupled therewith. This is occasioned by the fact that during adding operations the movement of the main differential member 27 is transmitted to the counting wheel 21 during the return movement of the former from its adjusted position adjacent the depressed key. Thus member 27 would move in a counter-clockwise direction in the course of entering amounts into the totalizers. On the other hand, in the course of taking totals in a machine of this type, as disclosed in detail in Patent No. 1,896,936, the counting wheels are in engagement with the differential mechanism during the forward movement of the latter. Thus, the clockwise motion of member 27 would cause a reverse motion of counting wheel 21, in a counter-clockwise direction as shown in Fig. 2. As the counting wheel 21 passes from position 1 to position 0, Figure 3, then its totalizing tens transfer tooth 45 formed by a prolonged normal tooth strikes and wipes underneath and rocks in a clockwise direction a companion tooth 46 and thereby causes double lever 42, 43, Figure 1, to rock so that roller 39 releases face 38 and the auxiliary differential actuator 36 becomes free, while arm 43 falls into the gap just opposite to its end, of the locking teeth 44 and holds the main differential actuator 27 in the position reached that corresponds to the position 0 of the counting wheel 21 coupled therewith. The execution of the rocking movement of lever 42, 43 is explained hereinafter.

The companion teeth 46, Figure 2, are allowed

to be in the path of the totalizing teeth 45 only with total taking operations of the machine, Figure 3. To this end the teeth 46 are swingingly mounted by means of pins 47, Figures 2 and 3, on carriers 48 rigid to journals 49. Each of these journals 49 has fixed on it an arm 51 which by a link 52 is in hinged connection with a plate 53 pivoted on a pin 26. A rod 54 is connected at one end to plate 53, and has an open slot 55 in its other end engaged by a pin 56 of a double lever 57. The latter in turn engages a cam groove disk 59, mounted on a gear shaft 58, Figure 2. On every operation of the machine one full clockwise revolution is imparted to shaft 58 in the course of which revolution the pin 56 is rocked first upward and then downward back to initial position. If the rod 54 assumes the position illustrated in Figure 2, it takes part in the motion of pin 56 so that all of the companion totalizing teeth 46, which in the position of rest of the machine are out of the path of the totalizer teeth 45, are rocked into the path of the latter at the beginning of the machine operation and again rocked out thereof in the course of the operation. Now when in the counterclockwise totalizing rotation of a counting wheel 21 the tooth 46 is urged outward the instant the wheel 21 passes from 1 to 0, this rocking motion of tooth 46 on pin 47 is transmitted by means of a link 61 to a lever 62 the free end 63 of which so acts upon a roller 64 mounted on a plate 65 pivoted on the journal 26 of the order concerned, that this plate by an inclined face 66 thereon acting on a roller 39' of a lever 42' causes the described rocking motion of the two-armed lever 42, 43, Figure 1, and thus release of the auxiliary differential actuator 36 and locking of the main differential actuator 27.

In order to cause engagement and disengagement of the companion totalizer tooth 46, Figure 2, only with total taking operations, the provision is made that these motions do not take place if an amount key is depressed. To this end the rod 54 is hingedly connected by a link 67 with an arm 68 rigid to a shaft 69, Figure 1. This shaft has further rigid to it below each row of amount keys 11 an arm 71 which by means of a pin 72 engages the bifurcated end of a rod 73 hinged to a slide 74 allotted to the row of amount keys concerned. Slide 74 by inclined slots 75 co-operates with lateral pins 76 of the amount keys and is shifted downward by depression of one of them, the rod 73 then imparting to arm 71 and shaft 69 a counterclockwise partial rotation. This causes a rocking motion of rod 54, Figure 2, so that it disengages pin 56 and by a bifurcated lug 77 engages a stationary pin 78. Upon an amount key 11 being depressed, rod 54 and therewith the totalizing companion teeth 46 are held in position of rest and cannot partake of the motion of lever 57.

As above mentioned, means is provided for controlling certain mechanisms to perform their functions only when taking a multiple item total, or when entering single item transactions. These mechanisms are under the control of the amount keys and the Sa key. Thus the depression of an amount key without depressing the Sa key, as when entering single item transactions, causes these mechanisms to operate; also the depression of the Sa key without the depression of an amount key causes them to operate. But the depression of both an amount key and the Sa key prevents their operation. The latter operation is for entering items of a multiple item transaction. Thus it is seen that the key Sa, in addition to selecting

the multiple item totalizer, also causes other mechanism to operate to obtain the proper results. This other mechanism is illustrated in Figure 4. In a manner resembling that illustrated in Figure 2, the shaft 69 which is rocked upon depression of an amount key 11, is connected by an arm 79 rigid thereto and a link 81 with a thrust rod 83 carried by a loose rocking arm 82. Rod 83 by its lower slotted end 84 engages a pin 85 of a three-armed lever 86, 87, 88 which by a roller 89 engages the curved groove of a disk 91 rigid to the gear shaft 58 and receives an oscillatory motion in each operation of the machine. The three-armed lever 86—88 is loose on a shaft 92 from which the drive of the mechanisms concerned is derived. An arm 93 is further rigidly connected to shaft 92 which arm by links 94, 95 is in hinged connection with the one arm, 96, of a two-armed lever 96, 98 loose on a fixed pin 97. Arm 98 has attached to it a thrust rod 99 connected by its other end to a slide 101 which by means of an inclined slot 102 cooperates with a pin 103 provided on the stem of the key Sa. Upon this key being depressed, which couples the totalizer on shaft 17 for operation, a clockwise swing motion is imparted to the two-armed lever 96, 98 so that link 95 is displaced to the left. Upon however an amount key being depressed, the rod 83 is swung to the right. Now rod 83 carries a lug 104 which co-operates with a lug 105 of link 95. In the position of the parts illustrated in Figure 4 in which neither an amount key 11 nor key Sa is down, the up and down motion of rod 83 caused by disk 91 does not exert any influence upon shaft 92, since lug 104 freely passes past lug 105. The machine operates from this setting of the parts upon the zeroizing of the sellers' totalizers mounted on shaft 16, corresponding to the sellers' keys 13, or of the main totalizer on shaft 15, corresponding to the key 14a. When rod 83 had been swung however to the right by depression of an amount key, the lug 104 thereon is moved into alinement with the lug 105, and upon subsequent downward movement of the rod 83, the lug 104 strikes lug 105 to rock link 95 about the pivot on the arm 96, to lower link 94 and to rock arm 93 and shaft 92 in a clockwise direction (Fig. 4). Therefore, when entering single item transactions; that is, an operation wherein an amount key 11 is depressed but the Sa key is not depressed, the shaft 92 will be rocked clockwise.

When taking a total of a multiple item transaction the Sa key is depressed, but no amount key 11 is depressed. Depression of the Sa key, through slide 101, link 99, and two armed bar 96—98, shifts the link 95 to the left (Fig. 4) to position the lug 105 beneath lug 104. Subsequent operation of the machine rocks the shaft 92, through cam 91, bar 86, stud 85, rod 83, lug 104, links 95 and 94, and arm 93.

When entering the items of a multiple item transaction, the shaft 92 is not rocked. As before mentioned, when entering an item of a multiple item transaction, an amount key 11 and the Sa key are depressed. Depression of an amount key 11 moves the lug 104 into alinement with lug 105, and the subsequent depression of the Sa key shifts the lug 105 to the left out of alinement with the lug 104. Therefore, upon operation of the machine with an amount key 11 and the Sa key depressed, the lug 104 misses the lug 105 and the shaft 92 is not rocked.

Thus it is clear that the shaft 92 is rocked only when single item transactions are entered, or when the total of a multiple item transaction is

taken. In all other operations the shaft 92 remains at rest.

The Sa key is held depressed during a series of multiple item entries, and this key stays down 5 until the total of the multiple item transaction is taken. For this reason a motor key Sx is provided to release the machine for the taking of the total of the multiple item transaction.

The Sa key is held depressed during the series 10 of item entries by a hook 107 of a detent 106, connected to the arm 93 by a pin and slot connection 109—111 on a link 108, the upper end of which link is connected to the detent 106.

Rocking of the shaft 92 during the multiple 15 item total taking operation serves to release the Sa key. Clockwise rocking (Fig. 4) of shaft 92, through arm 93 and link 108, lowers detent 106 to withdraw the hook 107 from the stud 103, to release the Sa key to its home or normal position.

20 Out of other mechanisms that can be actuated by shaft 92, first of all the item counters enter into consideration, because these counters are advanced preferably only when independent single items are entered or intermediate totals taken 25 of several items. The individual item counters 112, Figure 5, are advanced by oscillating pawl carriers 113 actuated by toothed segments 115 oscillating on fixed journals 114. The segments 115 in their turn are actuated by an arcuate swing 30 member 117 mounted on links 116 and having a rack 118. The latter is in mesh with a pinion 121 carried by a differential actuator 119 and is capable of being selectively brought to mesh with each of the segments 115. The setting of the differential 35 actuator 119 is performed by the following arrangement. A differential mechanism is arranged in the seller's key bank (Fig. 9) which resembles the differential mechanisms in the amount key banks with the exception that the parts 38 to 44 for causing an alternate locking of the differential members 27 and 36 are eliminated. By means of the differential mechanism shown in Fig. 9 the differential member 201 with 40 its pin 209 is set by means of the differential members 227 and 236 corresponding to the foot of one of the depressed keys 13. The setting member 201 is provided with a gear tooth portion 202 in mesh with a wheel 203 which serves to set the type wheels, and with another wheel 204 which is in further engagement with the wheel 45 205 to set the indicating members. The gear wheel 204 is fixed upon a shaft 206 which carries another gear wheel 207 (Fig. 5), meshing with the toothed portion 208 of the differential actuator 50 119 which selectively engages the item counters. By the above system of connections, the differential actuator 119 is always adjusted corresponding to the depressed keys 13, and thereby the desired item counter appurtenant the proper seller's 55 key is selected. When a downward motion is imparted to swing member 117, this motion is transmitted by pinion 121 to the segment 115 just engaged and therewith to the respective pawl carrier 113, so that the appurtenant item counter is advanced one unit. Now the motion of swing member 117 is caused by means of shaft 92. To 60 this end the lower link 116 is connected by a rod 122 with an arm 125 rigid to shaft 92.

In a similar manner the exhibiting and obturating 70 motion of the flash-plate of the displaying mechanism is controlled by shaft 92. The flash plate 126, Figure 6, is loosely mounted on the shaft 127 that carries the indicating rollers 128 and through rods 129, 131 and a two-armed lever 75 132 is hingedly connected to an arm 133. Under

the action of a spring 134 the flash plate tends to assume the exhibiting position shown in Figure 6. Arm 133 which is pivoted on a fixed pin 135, by a roller 136 cooperates with a cam disk 131 rigid to gear shaft 58 in such a manner as to have 5 imparted to it a downward motion at the beginning of an operation of the machine, from the position illustrated in Figure 6. In this lower position of arm 133 a recess 138 of a locking member 139 loose on shaft 58 engages the front 10 end of arm 133 so that it is locked in lower position and the flash plate 126 thus in obturating position. Hence, if the flash plate be not in obturating position already from the preceding machine operation, it is moved thereto at the beginning of each machine operation. Generally 15 no record can therefore be read off on the display rollers. Upon entering single items, however, or taking an intermediate total of several items, a partial rotation is imparted to shaft 92 as described. Shaft 92 has rigid to it an arm 141 which so co-operates with an arm 142 integral with locking lever 139 that upon shaft 92 rocking, lever 139 is swung to the left, arm 133 is released and flash plate 126 can rise to exhibiting position 20 under the action of spring 134. It results from the foregoing that the indicating rollers are not exhibited in taking grand totals from the main totalizer, in idle operations and in entering single items belonging to an intermediate total of several items.

The money drawer is to be released upon entry of independent individual items in the machine or when an intermediate total of several items is taken. The release is not desirable when the 35 individual items making up such an intermediate total are entered. Therefore, it is quite possible to derive the impulse for the release of the drawer from shaft 92. Furthermore, since the drawer is to be opened also with idle operations for the 40 purpose of changing money, it is necessary that the drawer mechanism be not only controlled by the amount keys and key Sa, but that the "clear" key may also release the mechanism. To this end shaft 92, Figure 7, has fixed to it an arm 143 45 that co-operates with a lateral lug 144 of a two-armed lever 145 rigidly connected to shaft 92. The lower arm of lever 145 carries a pin 146 normally embraced by an open slot 147 of a thrust rod 148. The latter is hinged to an angle lever 149 fulcrumed on a fixed shaft. The end of the upper arm of angle lever 149 engages an annular recess 151 of a rotatable and shiftable drawer releasing bar 152. This bar is selectively adjusted (in a manner not shown) to the different sellers' 55 drawers, while the drawer just selected is released by an upward motion of rod 152. It is evident that as long as the thrust rod 148 is engaging pin 146, the drawer is released upon introduction of single items and upon taking intermediate totals 60 of several items.

In order to have released the drawer also with idle operations, the thrust rod 148 by a rod 153 is connected to a slide 154 which by means of an inclined slot 155 co-operates with a pin 156 of 65 the "clear" key in such a manner that upon depression of the latter the front end of rod 148 is lifted. When this takes place, the open slot 147 releases pin 146. However another open slot 157 provided on an extension 158 riveted to rod 70 148, now engages from below another pin 159, Figures 4 and 7, which is coaxial with pin 146 but lies in another vertical plane and is carried by the three-armed lever 86, 87, 88. As described above, lever 86—88 engages by a roller 89 75

the grooved disk 91 of shaft 58, and, as an oscillatory motion is imparted to it in every machine operation, the release of the selected drawer takes place thus even when the "clear" key is depressed.

5 An error key 300, pivoted on shaft 301, is provided to release the erroneously depressed amount keys. When an amount key 11 is depressed, a hook on a detent 302 snaps over the stud of the depressed key in a well known manner. The detent 302 has pivoted thereto a link 303 provided with a shoulder to support a stud 304 on the error key 300. Depression of the error key lowers the detent 302 to release the depressed amount key.

Operation

15 A brief description of the operation of the machine will be given, referring more particularly to Fig. 8.

When entering amounts into the machine, the lever 12 must be in the upper or add position as shown in Fig. 12. Depression of one or more amount keys controls the differential actuators to add the amounts into the selected totalizers.

The totalizers are selected by special keys 13, 25 14a, and 14b. When a single item transaction is to be entered, the seller's key 13 is depressed, which, in addition to releasing the machine for operation by the motor, also selects the seller's totalizer on line 16, and the main totalizer on line 15. Therefore, when entering single item transactions, the amount thereof is added into two totalizers, one on line 15 and one on line 16.

When entering items of a multiple item transaction, the amounts are set on keys 11, and then key Sa is depressed and finally the machine is released by depressing a seller's key. At the end of the operation of any multiple item entry operation, the Sa key is held depressed. All the items are entered into the multiple item totalizer, line 17, into the selected seller's totalizer, line 16 and into the main totalizer, line 15.

When taking totals only one totalizer can be engaged at a time. When taking totals, the main totalizer on line 15 is selected by the key *; the seller's totalizers are selected by keys 13; and the multiple item totalizer is selected by the Sa key. The key *, and seller's key 13, are motor keys, so that, when taking totals from either the main totalizer or the seller's totalizers, only one key need be depressed.

When taking totals of multiple item transactions, it is necessary to depress two keys, i. e., keys Sa and Sx. Sa selects the proper totalizer and Sx acts to release the machine.

55 What I claim is:—

1. In a machine of the class described, a plurality of amount keys, a totalizer composed of counting wheels, a differential mechanism cooperating with said totalizer whereby amounts may be entered therein and the totals taken therefrom, an associated mechanism comprising a series of teeth cooperatively disposed with respect to said counting wheels of said totalizer, means for rocking said teeth into the field of operation of said counting wheels in the course of total taking operations, and connections actuated by the depression of an amount key for maintaining said teeth outside the field of operation of said counting wheels.

70 2. In a machine of the class described, a plurality of amount keys, a totalizer composed of counting wheels, a differential mechanism cooperating with said totalizer whereby amounts may be entered therein and the totals taken therefrom, an associated mechanism comprising a se-

ries of teeth cooperatively disposed with respect to said counting wheels of said totalizer, a rockable carrier for said teeth, a machine driven oscillating actuating member, connecting means between said member and said carrier to shift the latter and the teeth thereon into the field of operation of said counting wheels in the course of total taking operations, and means controlled by the depression of an amount key for disabling said connecting means whereby said teeth are maintained outside the field of operation of said counting wheels.

3. In a machine of the class described, a totalizer, manipulative means for controlling said totalizer for operation, manipulative means for 15 setting amounts to be entered in said totalizer, a member controlled by said first manipulative means, a second member controlled by said second manipulative means, means for actuating said second member in every machine operation, 20 and a shaft connected with the first member, said members being so adapted that the second-named member will actuate the first-named member and thereby actuate the shaft upon the operation of either one of said manipulative 25 means but not upon the operation of both.

4. In a machine of the class described, a totalizer, manipulative means for controlling said totalizer for operation, manipulative means for setting amounts to be entered in said totalizer, 30 a member, a lug on the member, said member adjusted by said first manipulative means, a link, a lug on the link, said link adjusted by said second manipulating means, means for actuating said link in every machine operation, and a shaft connected with the member carrying said first lug, said member and link being so adapted that the lug on the link will coat with the lug on the member and thereby actuate the shaft upon the operation of either one of said manipulative 40 means but not upon the operation of both.

5. In a machine of the class described, a totalizer, manipulative means for setting amounts to be entered in said totalizer, a differentially actuated mechanism for controlling said totalizer in 45 accordance with the amounts set by said manipulative means and adapted to be controlled by said totalizer at the zeroizing thereof, counting wheels forming said totalizer having tens transfer teeth, other teeth cooperating with said tens 50 transfer teeth at the zeroizing of said counting wheels, connections for rocking said other teeth into the field of operation of said tens transfer teeth at the beginning of every machine operation, and means for disabling said connections by 55 the operation of said manipulative means for setting amounts.

6. In a machine of the class described, a plurality of amount determining devices having effective and ineffective positions, a totalizer controlled in accordance with said amount devices, a total-taking mechanism therefor, actuating means, means, operated during the machine operation, whereby the actuating means renders said mechanism effective when the amount devices are all in ineffective position, and means for rendering said mechanism ineffective when an amount device is in effective position.

7. In a machine of the class described, a plurality of amount keys, a totalizer, main and auxiliary differential actuators for controlling said totalizer, a total-taking mechanism for obtaining the totals from said totalizer including means for alternately locking said main and auxiliary differential actuators, actuating means for said 75

locking means, driving means normally adapted to render said actuating means operative, and means for rendering said driving means ineffective when an amount key is in operative position.

- 5 8. In a machine of the class described, a plurality of amount keys, a totalizer with associated tens transfer teeth, main and auxiliary differential actuators for operating said totalizer, a total-taking mechanism for obtaining the totals from
10 said totalizer including means for alternately locking said main and auxiliary differential actuators, controlling means adapted to cooperate with said tens transfer teeth to control said locking means, actuating means normally adapted to
15 rock said controlling means into the path of said tens transfer teeth in every machine operation to render said total-taking mechanism operative, and means for rendering said actuating means ineffective when an amount key is in depressed
20 position.
9. In a machine of the class described, a plurality of amount keys, an actuating mechanism, control means for said mechanism, means whereby the control means is actuated at the depression of the amount key, an item totalizer, manipulative means for controlling the engagement of said item totalizer, another control means for said actuating mechanism actuated by said manipulative means, the two control means being so constructed and arranged that an operation of either, but not of both may cause an operation of said actuating mechanism.

10. In a machine of the class described, the combination of a plurality of amount keys, a totalizer, actuators for the totalizer, mechanism for controlling the actuators when taking totals, a drive means, connections between the drive means and said mechanism, and means actuated upon the depression of an amount key to disconnect said mechanism from the drive means.

11. In a machine of the class described, the combination of amount keys, a control key, a driving mechanism, a driven mechanism, and an interponent means to cause the driving mechanism to operate the driven mechanism upon depressing either an amount key or the control key.

12. In a machine of the class described, the combination of amount keys, a control key, a driving mechanism, a driven mechanism, a coupling mechanism to connect the driving mechanism to the driven mechanism, means actuated upon the depression of an amount key to move the coupled mechanism into coupled position, and means actuated by the subsequent depression of the control key to move the coupling mechanism into uncoupled position.

13. In a machine of the class described, the combination of amount keys, a driving mechanism, a driven mechanism, a lug on one member of the driving mechanism, a lug on one member of the driven mechanism, and connections actuated by the depression of an amount key to move the first lug into the path of the second lug whereby the driving mechanism actuates the driven member.

25 14. In a machine of the class described, a plurality of amount keys; an item totalizer; actuators therefor; manipulative means for controlling the engagement of the item totalizer with the actuators for entry of amounts into and the taking of totals from said item totalizer; total taking means for effecting a total taking operation from said item totalizer; mechanism associated with the total taking means to normally actuate the total taking means; and connections between the amount keys and the total taking means, and actuated by the depression of an amount key, to render the total taking means inactive.

ERNST BREITLING. 40
